UNITED STATES PATENT OFFICE

WILLIAM E. WINE, OF TOLEDO, OHIO

CAR-DOOR MECHANISM

Application filed August 1, 1928. Serial No. 296,699.

My invention relates to door mechanism for railway cars and is especially suitable for application to hopper cars, although it may advantageously be employed on cars of other type.

The principal object of the invention is to provide means which may be easily brought into operative association with the hopper door to maintain it in a plurality of different positions of closure for dampening the discharge of ballast and other similar lading.

The principal feature of the invention consists in associating with any suitable car door mechanism flexible means cooperable with the door so as to support the latter in different positions of closure for dampening the discharge of lading.

Another feature of the invention consists in connecting to an immovable portion of the car body a chain device, each of the links of the chain being cooperable with a projecting part of the hinged door for maintaining the latter in different positions of closure for dampening the discharge of lading.

Other and more specific features of the invention pertaining to advantageous forms of construction and combinations of parts will hereinafter appear and be pointed out in the claims.

In the drawings illustrating a preferred embodiment of the invention,

Figure 1 is a fragmentary side elevational view of a hopper side sheet and swingingly mounted door showing the invention applied thereto.

Figure 2 is a sectional view taken on line 2-2 of Figure 1.

Figure 3 is a fragmentary detail view, partly in section, showing the manner of securing the chain to the car body.

Figure 4 is a fragmentary detail view showing the manner of disconnecting the free end of the chain from a portion of the door mechanism.

While the drawings illustrate a single hopper and the adjacent edge of the co-acting door, it is to be understood that the construction is preferably duplicated on the

opposite side of the car and that the door illustrated is but one of a pair of doors connected by a spreader or stiffening member so as to swing as one.

In the drawings 1 is a sloping side sheet 55 of the hopper and 2 is the swinging door for closing the discharge opening thereof. The door may be secured to the car body in any desired manner (not shown) so as to swing to open position under the influence 60 of gravity.

Mounted upon the outer free face of the door adjacent the free edge of the latter is a door spreader or stiffening member 3 which may conveniently be of Z-shape having its upstanding leg 4 secured to the door by rivets 5 and its web 6 disposed substantially normal to the plane of the door. Rigidly attached to the web 6 by rivets 7 is a door arm member 8 which is offset intermediate its ends, as at 9, to pass around the outstanding marginal reinforcing flanges 10 of the door. The outer end of the door arm 8 is of substantially channel form having upstanding legs 11 and 12, respectively, the latter serving as a seat for cooperating with the hook 13 for maintaining the door in closed position.

Although the hook 13 which is pivotally connected to the door may be of any desired 80 form, I prefer to employ one having a plurality of ledges 14 and 15, respectively, for cooperating with the upstanding leg 12 of the door arm to support the door in partially closed and in fully closed position. Interposed between the pivoted hook 13 and the side sheet 1 of the hopper is a filler casting 16 which serves to space the hook outwardly from the latter so as to swing in a plane substantially parallel with the outer edge of the door and substantially normal to the main body portion thereof. Overlapping the outer face of the hook is a cover plate 17 having a plurality of inwardly projecting apertured lugs or thimbles 18, which engage the filler casting 16 for maintaining the cover plate in spaced relation thereto to permit free swinging movement of the hook.

Rivets 19, 20 and 21 are preferably employed for rigidly connecting the filler casting and 100

the cover plate to the side sheet of the hopper by passing through the respective apertured lugs of the cover plate. The apertured lugs which receive the rivets 20 and 21 in addition to functioning as spacing means serve as pivotal supports for the hook 13 and the rotatable cam 22, the latter being employed for locking the hook in door-supporting position.

10 The cover plate 17 may be fashioned with an outwardly projecting lug 23, which is apertured at 24 for receiving a removable lever to assist in moving the door to fully closed position. As is well known, the door may 15 be easily moved to a position such that it can be supported by the ledge 14 of the hook but considerable difficulty is often experienced due to warpage and distortion of doors of the character disclosed in moving the door to a final position of closure. Thus, after the door is supported by the ledge 14 of the hook, the removable lever may be inserted through the aperture 24 of the lug 23 into engagement with a portion of the outer end 20 of the door arm so that upon rotation of the lever in a clock-wise direction the door may be easily forced to closed position by the aid of the mechanical advantage thus obtained.

It is often desirable in discharging ballast 30 or the like from hopper or other similar railway cars, to control and dampen the discharge of the lading so that it may be deposited in pre-determined places in small quantities. To this end a chain of the usual type 35 having a plurality of links 25 may be employed. All of the links 25 of the chain are of uniform size, except the one designated by the numeral 26, which is secured to the car body by the plate or member 27, rivets 19 and 20 serving to attach the latter to the cover plate. At its forward end the member 27 is provided with an inwardly projecting lug 28 which is adapted to engage the outer face of the cover plate 17, the projection 28 being formed with a forward extension 29 to prevent rotation of the link 26.

Adjacent its outer end the upstanding leg 12 of the door arm is fashioned with a cut-out portion or slot 30 adapted to cooperate 50 with the links of the chain to support the door in various positions of closure to properly dampen the discharge of ballast and the like from the car hopper. The links are so proportioned that all with the exception of 55 the one adjoining the link 26 may be rotated a sufficient amount to permit them to alternatively be inserted in the slot 30. The manner in which the links respectively cooperate with the slotted end of the door arm will 60 be clearly understood upon reference to Figure 1 of the drawings wherein the door is clearly shown in dotted lines as being supported by the chain, also shown in dotted lines.

65 From the foregoing it will be apparent

that means is thus provided for supporting the door in any one of a plurality of positions whereby the discharge of lading may be damped. When it is desired to permit the door to swing open to the dotted line position shown in Figure 1, the link therein shown as cooperating with the door arm is inserted in the slot 30 of the latter before the hook is moved to door-releasing position. When this latter operation occurs, the chain will be moved into the dotted line position shown in Figure 1 and the door thereby supported as illustrated.

The member 27 employed for securing the chain to the car body is fashioned with a rearwardly projecting lug 31 for receiving one of the links 25 of the chain so as to support the latter in inoperative position. To prevent the chain from being accidentally disconnected from the lug 31 by the jarring or vibratory action of the car, the outer end of the lug is preferably enlarged, as clearly shown at 32 in Figure 4. When it is desired to disconnect the engaged link from the lug 31 it must be rotated through an angle of ninety degrees from the position shown in Figure 1 and then moved in the manner indicated in Figure 4.

From the foregoing it will be perceived that although the mechanism employed for dampening the discharge of lading is of simple and rugged construction it will efficiently perform its intended functions.

I claim:

1. In a railway car having a lading discharge opening, the combination with a door for closing the opening, the door being movable to open position under the influence of gravity, of mechanism for retaining the door in closed position involving a hook pivotally mounted on the car body and an arm rigidly secured to the door provided with an upwardly projecting flange engageable with the hook, said flange being provided with a slot, and a chain secured to the car body having a plurality of links, the latter being adapted to be inserted in said slot of the door arm to support the door in a plurality of positions of closure for dampening the discharge of lading from the car.

2. In a railway car having a lading discharge opening, the combination with a door for closing the opening movable to open position under the influence of gravity, of mechanism for supporting the door in closed position involving an arm carried by the door and a hook pivotally mounted on the car body, a cover plate overlying the outer face of the hook and provided with means affording a pivotal support therefor, a member secured to said cover plate, and a chain interposed between the said member and plate, said chain being cooperable with the said arm, upon disengagement of the hook therefrom, to support the door in a plurality

of positions of closure for dampening the discharge of lading from the car.

3. In a railway car having a lading discharge opening, the combination with a door for closing the opening movable to open position under the influence of gravity, of mechanism for supporting the door in closed position involving an arm carried by the door and a hook pivotally mounted on the 10 car body, a cover plate overlying the outer face of the hook and provided with means affording a pivotal support therefor, a member overlappingly secured to said cover plate having a portion spaced therefrom, means 15 extending between the spaced portions of said member and cover plate, and a chain carried by said means, said chain being cooperable with the door arm, upon disengagement of the hook therefrom, to support the 20 door in a plurality of positions of closure for dampening the discharge of lading from the car.

4. In a railway car having a lading discharge opening, the combination with a door for closing the opening movable to open position under the influence of gravity, of mechanism for supporting the door in closed position involving an arm carried by the door and a hook pivotally mounted on the 25 car body, a cover plate overlying the outer face of the hook and provided with means affording a pivotal support therefor, a member overlappingly secured to said cover plate, said member having an inwardly projecting lug abutting said cover plate, and a chain carried by said lug, the chain being cooperable with the door arm, upon disengagement of the hook therefrom, to support the door in a plurality of positions of closure for dampening the discharge of lading 30 from the car.

5. In a railway car having a lading discharge opening, the combination with a door for closing the opening movable to open position under the influence of gravity, of mechanism for supporting the door in closed position involving an arm carried by the door and a hook pivotally mounted on the car body, a cover plate overlying the outer 45 face of the hook and provided with means affording a pivotal support therefor, a member secured to said cover plate, and a chain interposed between the member and cover plate, said chain being cooperable with the 50 door arm, upon disengagement of the hook therefrom, to support the door in a plurality of positions of closure for dampening the discharge of lading from the car, said member being provided with a portion for supporting the chain in inoperative position.

In testimony whereof I affix my signature.
WILLIAM E. WINE.
